REED WITH DETACHABLE DENTS

James S. Hall, Methuen, Mass., assignor to Emmons Loom Harness Company, Lawrence, Mass., a corporation of Massachusetts

Application February 18, 1938, Serial No. 191,223

2 Claims. (Cl. 139—192)

This invention relates to all metal reeds for looms.

Reeds known as "pitchbacks" were formerly made of wood and twine and afterwards of segmental wooden bars with metal dents held in place between them. More recently all-metal reeds comprising parallel dents held together at their ends in various ways have come into use. The ends of the dents are rigidly held together 10 as by one or more ribs and a coil of wire, all three soldered together.

The purpose of this invention is to provide an all-metal reed which will have the flexibility of a "pitchback" or "wood and twine" reed, together with the wearing qualities of an all-metal reed, and one in which adjoining dents will yield to permit a slab on the warp thread to pass but will close up after its passage and in which a broken or injured dent can 20 readily be removed and replaced by another.

It is an improvement on the construction shown in the patent to Gourdeau, Spacing device for warps, No. 954,512, April 12, 1910 in which construction it was intended that a single dent could be removed and replaced, and on the patent to Horning, Loom reed and method and apparatus for its manufacture, No. 2,008,504, July 16, 1935, which shows two sets of large segmental wooden ribs with two large coils of wire and two sets 30 of small segmental metal ribs, each set rigidly soldered to a small coil of wire and to the dents which pass between the members of all four sets of ribs.

In my preferred construction, the edges of the 35 dents on the side of the reed which is next to the warp beam and which will first receive a slab are held less closely by the turns of a coil of wire than the edges on the side which is nearest the cloth. On the side of the reed which is 40 nearest to the cloth, the wire coils and half-round ribs are soldered, whereby a slab can more easily enter and gradually work its way through adjoining dents than if the entering edge was rigid, while the side which beats up the filling 45 preserves the desirable accurate spacing between the warp threads in the cloth.

I use dents with no notches and no blocks but hold them from slipping out endwise by split tubes so that by slipping off one tube any single 50 dent can be pulled out endwise and can immediately be replaced by a new one.

I also provide novel means to secure the headers firmly to fixed ribs at top and bottom but at one side only.

55 In the drawing, Fig. 1 is an elevation from the

front of a reed with parts broken away to show the construction.

Fig. 2 is an elevation from the back of a reed with parts broken away to show the construction.

Fig. 3 is an enlarged elevation of the top end 5 of a reed such as shown in Figs. 1 and 2.

Fig. 4 is an enlarged sectional elevation looking in the direction of the arrow on line 4—4 of Fig. 1.

Fig. 5 is an enlarged horizontal section looking down on the line 5—5 of Fig. 1.

Fig. 6 is an enlarged horizontal section looking down on the line 6—6 of Fig. 1.

Fig. 7 is a sectional view similar to Fig. 6 showing the parts of somewhat different sizes. 15

Fig. 8 is a view, not in section, similar to Fig. 7 of the modification.

Fig. 9 is an enlarged fragmentary elevation of a reed from the back with a dent being removed.

Fig. 10 is a view similar to Fig. 9 showing dents 20 bent at the end.

Fig. 11 is an enlarged elevation of the upper left hand end shown in Fig. 1 but with the covering tube removed.

Fig. 12 is a horizontal section looking down on 25 the line 12—12 of Fig. 11.

Fig. 13 is an enlarged detail view similar to Fig. 4.

In the drawing, H, H represent headers of substantially rectangular shape and made of 30 metal, each having near each end and on the outside a substantially rectangular recess or notch I. D, D represent dents of the usual construction of flat thin metal.

Near each end of the dents on the front and 35 back is a set of large ribs L and L¹. Of these, L is soldered and L¹ is free and preferably at the back. The two ribs near each end form a set. Both ends such as 2, 2 of the ribs L, L¹ are bent at right angles into the header recesses I, I as 40 shown in Figs. 11 and 12.

C, C represent large coils of wire each of which 45 enclose each set of two large ribs L, L¹. As shown, there is a turn 3 of each coil between each two adjoining dents such as D, D. The diameter of the wire of each coil may be exactly the same as the space between the dents or, as shown in Fig. 7, the diameter may be less than that space.

A, A¹ represent small segmental ribs of which 50 there are two sets, each set including two ribs, A being soldered and A¹ being free. Each set of small ribs is located nearer the middle of the reed than the large sets of ribs L, L¹ and each set of small ribs is enclosed by a small coil of wire F. As shown, each turn 4 of each small 55

coil passes between the adjoining dents and, as shown in Figs. 1 to 6, the wire of both coils C, C is of a diameter to exactly fill the space between the adjoining dents.

5 The wire of each coil F preferably is of slightly less diameter so that the dents may yield slightly sideways but will immediately be brought back to alignment, as after a slab has passed.

10 On one side of the reed, which I will call the front, the curved surface of the large rib L on that side is soldered by solder S to the adjoining part of coil C and the curved surface of the adjoining small rib A is soldered to the adjoining part of coil F, this solder also extending between 15 the turns of coils C and F and between the adjoining ribs L and A at 12.

20 This solder represented by S extends from the outer edge 10 of a large rib along the line which coincides with the front edge of the row of dents around the curved surface and between the dents of the coil to the inner edge of the large rib at 11, thence at 12 across to the outer edge 13 of the adjoining small rib, thence around the curved surface of this rib and between the turns of the 25 coil F to the inner edge 14 of the small rib. The solder, therefore, makes a rigid front at the top and bottom from which the free parts 7, 8 of the coils C and F project. If the solder does not touch the dents, it is clear that by removing all 30 four of the ribs, L¹, L¹ and A¹, A¹, one dent or many dents can be lifted out from the back side when it is necessary to make repairs and others can be put in their places, after which the four 35 ribs can be replaced.

35 As shown in Fig. 9, without removing any of the ribs, if there were no cap such as T or by removing the cap, any individual dent can be pulled out without touching any of the ribs.

40 However, to prevent dents from dropping out from between the coils and ribs, I use a special cap at the top and bottom in the form of a split tube T, the split 38 being of a width to fit the space between the large and small ribs and large and small coils, engaging the solder along the 45 line 12. Preferably the end 31 of each dent touches or is close to the inside of this cap as shown in Fig. 3.

45 In place of using such a cap or with it, however, I can use what is known as a "cornish", shown at 32 in Fig. 10. This cornish is the bend at the end of each dent and this holds it in place from slipping out but at the same time, by removing the four ribs, it can be removed from the back.

50 The arrangement of the parts is shown diagrammatically in Figs. 5, 6 and 7.

55 Preferably the diameter of a wire of coil F is slightly less than that of coil C. As shown in Fig. 6, there is no space between the turns of wire C and the dents, although actually there is usually a small space, but there is a space between the dents and the turns of coil F, as shown

in Fig. 5, so that each dent can move a little laterally and adjoining dents can open up slightly so as to allow a slab to pass. Actually there can be a slight lateral yielding of the free part of the turns of the wire C. Such a slight yielding is desirable, especially at the back or the free side of the coils which preferably is nearer the warp beam than the fixed or front side which is toward the cloth. This allows thick places and slabs to pass more readily.

10 As shown in Fig. 7, in some cases I prefer to leave spaces between the turns of a large coil such as N and the dents P so that while the front side where the rib M is fixed and soldered to the coil by solder S is rigid, the dents N can move slightly to the right or left or turn but will always come back substantially in place although the spacing between the warp threads in the cloth will always be uniform and without streaks.

15 In some cases, as shown in Fig. 8, I may use 20 dents such as B which are thicker at one edge than at the other. In such a case, I preferably locate the thick edge 20 next to the fixed rib A rather than the loose rib A¹.

25 I claim:

1. In a reed for looms, the combination of parallel headers, each of rectangular cross section and each having a notch in the upper outside edge; with two outside parallel sets of large segmental metal ribs, one end of each member of each set being bent into a notch; a large coil of wire enclosing each set of large ribs and soldered to the cylindrical surface of one rib of each set, the turns of each coil being oppositely wound; two inside parallel sets of small segmental metal ribs; a small coil of wire enclosing each set of small ribs and soldered to the cylindrical surface of one member of each set, the turns of each small coil being oppositely wound; dents passed between the turns of all four sets of coils, between 30 a soldered rib and an unsoldered rib, the outside end of each dent being bent to hold it in place; and a cover formed of a longitudinally split metal tube, the edges of the split coming between a large and a small coil.

2. In a reed for looms, two outside parallel sets of large segmental metal ribs; a large coil of wire enclosing each set of large ribs and soldered to the cylindrical surface of one member; two inside parallel sets of small segmental metal ribs positioned inside the large ribs; a small coil of wire enclosing each set of small ribs and soldered to the cylindrical surface of one member thereof, the solder extending between the large and small ribs and coils and outside the dents; headers connecting and holding together all of said parallel segmental ribs; and dents passed between the turns of all four of the coils and between the soldered and the unsoldered segmental ribs of each set.

60 JAMES S. HALL.
